US00D643290S

(12) **United States Design Patent**
Braun et al.(10) **Patent No.:** **US D643,290 S**
(45) **Date of Patent:** **** Aug. 16, 2011**(54) **CONTAINER**(75) Inventors: **Jason A. Braun**, Lake Hiawatha, NJ (US); **Farhad Alibhai**, Toronto (CA); **Derek J. Romeo**, Ridgewood, NJ (US); **Mark J. Ramundo**, Waldwick, NJ (US)(73) Assignee: **Kraft Foods Global Brands LLC**, Northfield, IL (US)(**) Term: **14 Years**(21) Appl. No.: **29/385,714**(22) Filed: **Feb. 18, 2011****Related U.S. Application Data**

(60) Division of application No. 29/357,740, filed on Mar. 16, 2010, now Pat. No. Des. 635,458, which is a continuation-in-part of application No. 29/339,545, filed on Jul. 1, 2009, now Pat. No. Des. 614,034.

(51) **LOC (9) Cl.** ..... **09-01**(52) **U.S. Cl.** ..... **D9/500; D9/516; D9/537**(58) **Field of Classification Search** D9/500, D9/502, 516, 520, 530, 537-540, 545, 546, D9/549, 551, 556, 558, 564, 574, 575; 215/379, 215/381-385; 220/600, 608, 660, 669, 675

See application file for complete search history.

JP 2000043874 2/2000

(Continued)

Primary Examiner — Stella Reid*Assistant Examiner* — Elizabeth J Oswecki(74) *Attorney, Agent, or Firm* — Fitch, Even, Tabin & Flannery(57) **CLAIM**

The ornamental design for a container, as shown and described.

DESCRIPTION

FIG. 1 is a perspective view of a container showing our new design;

FIG. 2 is a front elevation view thereof, the rear, left side, and right side being an identical image;

FIG. 3 is a bottom plan view thereof; and,

FIG. 4 is a top plan view thereof.

Portions of the container shown in broken lines in the figures are for illustrative purposes only and form no part of the claimed design.
